ABSTRACT

A telegraphy retransmitter receives bipolar modulated signals interrupted by telegraphic modulation equipment and retransmits the bipolar modulated signals without the interruptions. The retransmitter employs polarity sensitive transistor switching circuits and a holding circuit for maintaining the desired level of the bipolar signal during the period of the interruptions, so that the period of interruption is effectively eliminated.

FIG. 1

FIG. 2

FIG. 3

FIG. 4

**RETRANSMITTING APPARATUS FOR CONVERTING
INTERRUPTED TELEGRAPHIC MODULATED SIGNALS
INTO TELEGRAPHIC SIGNALS WITHOUT
INTERRUPTIONS**

The invention relates to a modulation retransmitter, more particularly a telegraphic modulation retransmitter, which receives at the input a modulation (for example bipolar modulation), in which the elementary signals may be affected by some deformation, and which retransmits this modulation (for example in single polar current) with elementary output signals reshaped in accordance with their theoretical curve.

It is known that bipolar current telegraphic modulation appears in the form of signals formed by the combination of several pulses, either negative or positive with respect to ground, the center point of the telegraphic battery.

The device according to the invention makes it possible to restore at the output a voltage close to ground for positive polarity at the input, and absence of output polarity for a negative polarity at the input, the converse arrangement being obviously selectable without modifying the principle of the invention.

According to the theoretical trace of bipolar modulation signals, there is no passage of time between a moment of a certain polarity and a moment of opposite polarity; now, in practice a passage of time could not be zero without giving rise to a short circuit between the two terminals of the battery.

In fact, the passage of time from one polarity to the other, may also be called break time and which corresponds to a time in which no polarity is retransmitted, is not negligible; for example, for a telegraph relay, the passage of time from one contact to the opposite contact may be of the order of 1 millisecond. Similarly, the design of the transmitting device of some teleprinters provides a break time not only between two consecutive moments of different polarity, but also between consecutive moments of the same polarity.

It is clear that independently of the distortion of signals caused by their transmission, a systematic deformation is involved, due to the very fact of their mode of generation.

It is the aim of the present invention to remedy these disadvantages by providing a device which supplies output signals reshaped according to their theoretical curve.

The retransmitter device according to the invention is characterized more particularly in that it comprises a line polarity detection device and an output device having a time constant, maintaining the output state constant for a certain time after the disappearance of the input polarity.

According to one feature of the invention, the device comprises substantially four transistors, a capacitor and resistances, two transistors being assigned, for example, to the detection of positive line polarity, one transistor being assigned to the detection of negative line polarity, and one transistor being assigned to the output signals, the capacitor enabling a time constant to be obtained in the change of state of the output transistor.

According to another feature of the invention, the detection of a negative line polarity produces, on the one hand, blocking of the output transistor and, on the other hand, rapid discharge of the capacitor; during the break following the polarity, the output transistor remains blocked and the capacitor remains discharged, all the detection transistors being then blocked.

Other features of the invention will appear from the following description of an embodiment of the invention given as example, by no means restrictive, with the aid of corresponding drawings, in which:

FIG. 1 shows a theoretical trace of bipolar modulation for a code combination;

FIG. 2 shows the real trace of bipolar modulation of the same combination obtained with the transmission device of certain teleprinters;

FIG. 3 shows a real trace of single polarity modulation of a retransmitter device in which the output control depends directly on one of the input polarities;

FIG. 4 shows the real trace in single polarity modulation obtained with the device according to the invention;

FIG. 5 shows an electric circuit diagram of a device according to the invention.

It is assumed, by way of example, that FIG. 1 relates to a telegraphic code combination comprising three positive moments M1, M2 and M3 and two negative moments M4 and M5; in addition the "start," always negative, and the "stop," always positive. The whole of the seven moments corresponds to a character of the international telegraph code. In bipolar operation, the top horizontal line corresponds to positive polarity of the telegraph battery, the bottom horizontal line corresponds to negative polarity of the telegraph battery, the middle horizontal line corresponds to zero ground potential of the middle point of the battery. The trace shown in FIG. 1 is a theoretical trace since at the same instant, t_0 for example, the line is simultaneously positive, negative or at zero potential, which is obviously impossible. In fact, if the line is sometimes connected to negative polarity by means of a flexible contact blade, there is a certain nonnegligible time of travel from one contact to the other; during this time of travel the line is therefore not connected to any polarity and is therefore at earth potential by its other end.

FIG. 2 is a real trace of the modulation received in FIG. 1. It will be seen that the vertical line 1 determines the passage to negative and the vertical line 2 the return to positive, the effective duration between the time t_1 (positive) and the time t_3 (negative) being effected by means of a nonnegligible time t_2 , during which the line is at zero potential. Similarly, the return to positive of the time t_5 is effected by means of a nonnegligible time t_4 , during which the line passes through zero potential again. The times t_2 and t_4 represent the time taken by the moving blade contact to travel from the positive contact to the opposite negative contact. In telegraph relays, when the movable armature has been deflected by the effect of the change in direction of the current in the coil, a permanent magnet keeps it in its new position until a fresh reversal of current in the coil brings the movable armature into the opposite position. If there are several successive moments of the same sign, the armature thus remains in fixed position on the last polarity received. However, a break time, such as t_2 or t_4 , which exists only because there is a change in the line polarity, is produced because of the electromechanical design of certain teleprinters, even when there is no change in polarity. Thus, this is the case of the break time t_6 , for example, situated between the positive times t_5 and t_7 . FIG. 2 is therefore quite appreciably different from the theoretical trace of FIG. 1.

FIG. 3 again shows the same modulation as in FIG. 1 but with single polarity operation, that is to say, the upper horizontal line represents the time intervals during which the transmission line is connected to a weak polarity p close to ground, while the lower horizontal line represents the time intervals during which the transmission line is connected to positive or negative polarity originating from the utilization circuit. The polarity assumed here is negative polarity, but this choice is not obligatory. If the output control of the retransmitter device depends directly on the input polarity (positive, for example) all the disconnections are interpreted as the opposite polarity (negative, for example). The result is a distortion of the signals, due to spread of the negative moments (for example). On the other hand, there are obviously breaks between consecutive moments of the same polarity.

FIG. 4 shows single polarity modulation such as is obtained with the device according to the invention. The break times received at the input of the double current device have no repercussion on the single current output; to obtain this result, the change in output polarity must be controlled only by a change in polarity at the input and not by the break in polarity of the preceding moment.

In the embodiment shown in FIG. 5, the bipolar signals arrive at the input E by a line L. They leave the device again by an output S and are utilizable by a load impedance R_L which may represent any receiving element.

Successively in series with the line L are the input E, are a diode D_1 and a diode D_2 , the end of the line opposite to the input being grounded. The diodes D_1 and D_2 are connected in

opposite directions, the diode D_1 having its cathode directed towards the input and the diode D_2 having its cathode grounded. The input E of the line is also connected to the emitter of a transistor T_1 whose base is connected to the anode of D_1 ; the cathode of the diode D_2 is also connected to the emitter of a transistor T_2 , whose base is connected to the anode of D_2 ; the bases of T_1 and T_2 , at a common point on the line, are therefore at the same potential. The transistors T_1 and T_2 are of PNP-type. The collector of T_1 is connected to the base of a transistor T_3 , of NPN-type, through a resistance R_1 , the base of T_3 being also connected to negative polarity through a resistance R_2 . The emitter of T_3 is connected directly to negative polarity and the collector of T_3 is connected through a diode D_3 to a common point M . At point M two circuit branches are connected; the first formed by a resistance R_3 , whose end N is connected to one plate of a capacitor C , whose other plate is grounded; the second branch connects the point M to the base of a transistor T_4 of PNP-type through a resistance R_5 , the base of T_4 being also grounded through resistance R_6 . The collector of the transistor T_2 is connected to the point N through diode D_4 and resistance R_4 . Finally, the emitter of transistor T_4 is connected to a slightly negative bias voltage p ; its collector, connected directly to the output S , has negative polarity across the load impedance R_L .

The operation of the device just described is as follows:

It is assumed, for example, that the device according to the invention receives a bipolar modulation according to FIG. 2, that is to say, the operation will be described at the different times $t_1, t_2, \dots, t_7$.

In the time t_1 :

The line L is at positive polarity. The diode D_1 appearing in reverse characteristic, that is to say with a high internal resistance, a weak reverse current passes through the diode D_1 and, practically, the potential of the portion of line situated between the two diodes is positive with respect to ground. The transistor T_1 , having its emitter at the telegraphic positive polarity, which is positive with respect to the base, becomes conducting, but the transistor T_2 , having its base positive with respect to the emitter, remains blocked. The diode D_2 is conducting, its anode being positive with respect to its cathode. The base of transistor T_3 , due to the voltage drops in the resistances R_1 and R_2 , assumes a negative potential intermediate between ground and negative polarity. This potential, being less negative than that to which the emitter of T_3 is connected,

emitter negative with respect to its base, remains blocked, and consequently so does the transistor T_3 . Transistor T_2 , on the contrary, having its emitter grounded and its base negative, becomes conducting. The resistance R_4 being of fairly low value, the capacitor C is rapidly discharged through R_4, D_4 and transistor T_2 . Ground potential across T_2, D_4, R_4, R_3 and R_5 is thus connected to the base of transistor T_4 ; since the emitter of T_4 is negative with respect to the base, transistor T_4 is blocked. The output S therefore assumes negative polarity across the impedance R_L of the utilization circuit.

In the time t_4 :

The time t_4 is a break time, during which the line L does not receive any polarity, either positive or negative. Transistors T_1 and T_3 remain blocked; transistor T_2 is blocked. Transistor T_4 remains blocked. The output S , therefore, continues to be negative across the impedance R_L . Capacitor C is kept discharged by the circuit R_3, R_5, R_6 and ground.

In the time t_5 :

As in the time t_1 , the line L is at positive polarity. In a manner similar to that occurring in the time t_1 , transistors T_1 and T_3 become conducting, transistor T_2 is blocked. Capacitor C is rapidly charged through resistance R_3 and diode D_3 , resistance R_3 being rather low. Transistor T_4 becomes conducting, its base assuming a negative potential in the circuit formed by T_3, D_3, R_5 and R_6 . The output S substantially assumes the bias p of the emitter of T_4 .

In the time t_6 :

The time t_6 is a break time. Transistors T_1 and T_3 are blocked; transistor T_2 remains blocked. The capacitor C is discharged through the resistances R_3, R_5 and R_6 and during its discharge maintains transistor T_4 conducting. This state is maintained beyond the normal break time. The output S , therefore, retains during the break the potential p which it had during the preceding time t_5 .

In the time t_7 :

The line being at positive potential, transistors T_1 and T_3 become conducting, transistor T_2 is blocked. Capacitor C , partly discharged, is recharged rapidly through the resistance R_3 and diode D_3 . Transistor T_4 is maintained in the conducting state by the circuit consisting of T_3, D_3, R_5 and R_6 . The output S , therefore, during the time t_7 , retains the slightly negative potential which it had during the preceding times t_5 and t_6 .

Finally, the following table may be drawn up

Time t_1	Time t_2	Time t_3	Time t_4	Time t_5	Time t_6	Time t_7
Output S potential p	Potential p	Potential across R_L	Potential across R_L	Potential p	Potential p	Potential p

renders transistor T_3 conducting. The capacitor C is charged through the diode D_3 and the resistance R_3 . On the other hand, the base of transistor T_4 assumes a certain negative potential owing to the voltage drops in the resistances R_5 and R_6 . The voltage of the base being negative with respect to the emitter, transistor T_4 becomes conducting. The output S therefore assumes a potential very close to p .

In the time t_2 :

The time t_2 is a break time when, consequently, the line L does not receive any polarity, either positive or negative. Transistors T_1 and T_3 are blocked; transistor T_2 remains blocked. The capacitor C is discharged across the resistances R_3, R_5 and R_6 , and during its discharge keeps the transistor T_4 conducting. The time constant is calculated such that this state persists beyond the normal break time, the resistance R_5 being of fairly high value for this purpose. The output S therefore retains the potential p which it had during the time t_1 .

In the time t_3 :

The line L is at negative polarity. The diode D_1 is in forward characteristic but the diode D_2 is in reverse characteristic, that is to say, with a high internal resistance; a weak reverse current passes across the diode D_2 and, practically, the potential of the portion of line situated between the two diodes is very close to the negative of the line. Transistor T_1 , having its

which corresponds exactly to the curve shown in FIG. 4.

It will be seen that this curve has the same profile as the theoretical curve of FIG. 1; however, the upper horizontal line of FIG. 1, which represented the telegraphic positive, in FIG. 4 represents a bias potential p , and the lower horizontal line, which in FIG. 1 represented the telegraphic negative, in FIG. 4 represents the negative polarity across the utilization resistance R_L .

It is obvious that it will not be going outside the scope of the invention to use elements giving equivalent results, in particular to use transistors of opposite type combined with another orientation of the diodes and supplies. Similarly, reversal of the polarities on the output curve of the device obviously remains within the scope of the invention. 12

I claim:

1. An apparatus for retransmitting a bipolar signal, which contains interrupted portions, the voltage level of said interrupted portions being different from the voltage levels defining the amplitudes of the bipolar signal comprising:

first means for receiving said bipolar signal in its interrupted form;

second means responsive to said first means for maintaining the voltage level of the bipolar signal, immediately

preceding said interrupted portion, for the duration of said interrupted portion, thereby eliminating the interruption; and
 third means responsive to said second means for delivering said bipolar signal at an output with said interrupted portion of said bipolar signal removed, so that said signal varies between only two levels defining the amplitude of the retransmitted bipolar signal.

2. An apparatus according to claim 1, wherein said second means includes a polarity sensitive transistor circuit, connected to said third means and responsive to the polarity of the received interrupted signal, for eliminating the interrupted portion from said bipolar signal.

3. An apparatus according to claim 2, wherein said transistor circuit includes a first and second transistor switching circuit, a holding circuit and a third transistor switching circuit, said first and second transistor switching circuits providing a charging and discharging path respectively, for said holding circuit and wherein said third transistor switching circuit is connected to and controlled by said holding circuit through a discharge circuit having a time constant greater than the duration of the interrupted portion of said bipolar signal.

4. An apparatus according to claim 2, wherein said first means includes a pair of polarity sensitive diodes connected to said polarity sensitive transistor circuit.

5. An apparatus according to claim 3, wherein said first transistor switching circuit includes a charging transistor and a

charging diode, providing a charging path to said holding circuit.

6. An apparatus according to claim 3, wherein said second transistor switching circuit is connected through a discharging diode to said holding circuit providing a discharge path from said holding circuit.

7. An apparatus according to claim 4, wherein said transistor circuit includes a first and second transistor switching circuit, a holding circuit and a third transistor switching circuit, said first and second transistor, switching circuits providing a charging and discharging path, respectively, for said holding circuit and wherein said third transistor switching circuit is connected to and controlled by said holding circuit through a discharge circuit having a time constant greater than the duration of the interrupted portion of said bipolar signal.

8. An apparatus according to claim 7, wherein said first transistor switching circuit is connected through a charging transistor and a charging diode to said holding circuit, providing a charging path to said holding circuit.

9. An apparatus according to claim 7, wherein said second transistor switching circuit is connected to a discharging diode, providing a discharge path from said holding circuit.

10. An apparatus according to claim 8, wherein said second transistor switching circuit is connected through a discharging diode to said holding circuit, providing a discharge path from said holding circuit.
